(57) **CLAIM**

The ornamental design for a camera with flip-up flash, as shown and described.

DESCRIPTION

FIG. 1 is a front, top, right-side, perspective view of a camera with a flip-up flash according to our new design, showing the flash flipped down;

FIG. 2 is a rear, bottom, left-side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right-side elevation view thereof;

FIG. 8 is a left-side elevation view thereof;

FIG. 9 is a front, top, right-side perspective view thereof, showing the flash flipped up; and,

FIG. 10 is a rear, bottom, left-side perspective view thereof, showing the flash flipped up.
